JESS V. WINTER, OF LA CROSSE, WISCONSIN.

DECOY DUCK.

Application filed May 1, 1926. Serial No. 105,896.

The invention relates to decoy ducks.

An object of the invention is to produce a decoy duck for the use of hunters that shall be very simple and inexpensive in construction, and that is so made that it may be taken apart and packed in a flat package that is very compact, and of light weight that it may be easily transported in quantities; and that may be easily and quickly taken apart and reassembled, and yet be firmly held in assembled condition when put together.

Another object of the invention is to furnish a decoy duck of comparatively thin material compactly held together and furnished with a balancing mechanism that will prevent wind and waves from tipping it over when in the water. It is a further object of the invention to provide a balancing device that may be readily removed when the decoy is being packed for transportation, and as readily replaced to give the desired balancing effect.

In the drawings,

Fig. 1 is a side elevation with the parts secured together for use.

Fig. 2 is a side elevation with parts disconnected, and showing the means by which the parts are connected together.

Fig. 3 is a front with the balancing means in place.

Fig. 4 is a front elevation, the balancing means in place.

Fig. 5 is a plan.

Fig. 6 indicates the balancing means detached.

In the drawings, the numeral 1 shows the top portion of the decoy duck made in accordance with my invention, the top part being detachable from the bottom portion, as shown in Fig. 2; the numerals 2 are pins secured vertically in the body of the top, and projecting upwardly into the same and projecting downwardly a distance below the top part, as indicated in dotted lines in Fig. 1 and in full lines in Fig. 2. It will be observed from examination of Fig. 2 that the projecting parts 3 of these pins are not parallel with each other, but are spaced further apart at their free ends than they are where they enter the wood of the top portion. The numerals 4 indicate stiffening members vertically placed in the wood of the top to cross the grain. Numerals 5 are vertical sockets passing into the transverse central portion of

the lower portion of the decoy, this lower member, 7, being horizontal with respect to the top member, and is secured to the top member along the longitudinal median line of the bottom part, as shown in Fig. 5. The sockets 5 are shown as being in the bottom member 7 and parallel with each other; but inasmuch as the pins 3, while spaced to enter the sockets 5, because of their angular relation to the sockets, will have a pinching or binding effect on the sides of the sockets, because they are not parallel with the sides of the sockets. This relation is clearly shown in Fig. 1, there being something also of a springing effect of the pins with respect to the sockets as the pins are crowded down into the sockets. It is not necessary to have much of an angular departure from the vertical in the pins and of course, the sockets might have a slight angular setting and the pins depend perpendicularly from the bottom of the top member, 1; the object being to have the pins and sockets arranged so that as the pins 3 enter the sockets there shall be a binding relation between the two. The angular relation is very cheaply made and is very efficient. It would, however, be within the scope of the invention to have the pin and socket have a mere frictional relation, without the peculiar binding or springing force.

The numeral 6 indicates a vertical aperture in the bottom of the horizontal portion 7 from the bottom thereof, which is shown as passing entirely through the bottom portion, but which is not necessary. The numeral 8 indicates a vertical member having a threaded upper end adapted to be secured in the vertical aperture 6, the lower end of this member being provided with an enlargement to give more weight. The object of this member 8 is to furnish a balancing member depending vertically below the bottom of the decoy, to steady it in proper position, and prevent the decoy from being tipped over by winds and waves, when placed in the water for use.

The top and lower sections of the decoy are so made that when separated they may be packed with one part lying flat upon the other and so occupy a very small amount of space. For assemblage, all that is necessary is to push the pins 3 down into the sockets 5, when the upper and lower portions will be securely fastened together, and to screw the member 8 into the vertical opening 6

in the horizontal portion—all of which can be done in a few seconds of time. Inasmuch as the body of the decoy is made of very light weight, a considerable number 5 of decoys can be carried in sacks or otherwise a long distance on the back of a hunter without materially tiring him; and they can be packed in a very small compass, so as to occupy little space in a boat. Preferably 10 the members 2—3 are made so that they will spring in being forced into the sockets 5.

Having now described my invention, what I claim is:

1. In a decoy duck, the combination of 15 flat separable portions comprising vertical and horizontal elements, with means for securing the bottom of the vertical portion to the upper face of the horizontal portion comprising pins and sockets in the respective 20 elements having a pinching contact with each other when in position.

2. In a decoy duck, the combination of a vertical upper portion and a horizontal lower portion, with means for securing the 25 bottom of the upper portion to the lower portion, comprising pins and sockets arranged upon the respective portions, the pins and

sockets having an angular relation to each other.

3. In a decoy duck, the combination of a 30 separable vertical upper portion and a horizontal lower portion with means for securing the portions together comprising male and female elements having a springing relation to each other.

4. In a decoy duck, the combination of a vertical upper portion and a horizontal lower portion, with means for securing the two 35 portions together comprising pin and socket connections having springing relations with each other when in position.

5. In a decoy duck, the combination of 40 separable vertical and horizontal portions, with means for securing the two portions together along the central longitudinal line 45 of the horizontal portion, and a balancing device projecting downwardly from the bottom of the horizontal portion on the transverse central portion thereof, said balancing member having a threaded upper end, and the horizontal portion being adapted to receive the threaded end portion of the balancing device for holding purposes.

JESS V. WINTER.
